UNITED STATES PATENT OFFICE.

DAVID STEPHENS, OF RUSHVILLE, ILLINOIS.

CHURN.

SPECIFICATION forming part of Letters Patent No. 406,791, dated July 9, 1889.

Application filed February 27, 1889. Serial No. 301,323. (No model.)

To all whom it may concern:

Be it known that I, DAVID STEPHENS, a citizen of the United States, residing at Rushville, in the county of Schuyler and State of Illinois, 5 have invented new and useful Improvements in Churns, of which the following is a specification.

My invention relates to improvements in churns; and it consists in certain novel features hereinafter described and claimed.

In the accompanying drawings, Figure 1 is a perspective view of a churn embodying my invention. Fig. 2 is a front view showing the churn-body in vertical section, and Fig. 3 is a 15 detail perspective view of the driving-shaft and the oscillating levers actuated thereby.

Referring to the drawings by letter, A designates a suitable base, on the upper side of which I secure, by means of the brackets or 20 angle-irons B, the standards C D, the said standards being suitably braced by the beams E, as shown. The inner standards C are extended somewhat above the outer standards D, and between the upper ends of said inner 25 standards I mount a spool or idle-pulley F.

The upper end of the churn-body G is closed by a lid I, of any desired construction, and the dasher-rod J passes centrally through the said lid. The said dasher-rod is mounted in 30 notches K in the ends of the bearing-blocks L, secured between the upper ends of the standards C, and oscillates in said notches and is held in a vertical position thereby. The dasher-blades M are secured to the lower 35 end of the dasher-rod by means of the radial arms N, projecting from the dasher-rod, and are arranged at an angle to the said arms, so that they will effectually agitate the cream and gather the butter.

40 Near the lower ends of the standards E, I secure the transverse pivot-pin O, on which I pivot the lower ends of the oscillating levers P, which extend upward between the said standards, and are provided near their upper ends with the longitudinal slots Q. A double crank-shaft R is journaled in the upper ends of the standards D, and has its crank-arms passing through and engaging the said longitudinal slots of the oscillating levers, so 45 that when the said shaft is rotated the levers will be oscillated, as will be readily under-

stood. The shaft is provided at one end with an operating-handle S, and the lateral portions or legs of its crank-arms are flattened, so as to engage the opposite sides of the levers and prevent them from moving longitudinally on the said crank-arms. The slots of the levers may be formed along the central lines of the same; but I prefer to form them by making elongated notches or recesses in 55 the inner sides of the levers, and then securing guard-plates U over the said recesses, as shown. This construction permits the more ready disengagement of the levers and the driving-shaft in the event of either being 60 broken.

The upper ends of the levers are connected with the dasher-rod by a belt V, which has one end secured to the upper end of the levers, thence extends over the idle-pulley F to 70 the dasher-rod, around which it is wrapped tightly a number of times, and then passes backward under the idle-pulley to the upper end of the other lever to which it is secured.

From the foregoing description, taken in 75 connection with the accompanying drawings, it is thought the operation and advantages of my churn will be readily understood. The cream to be churned is placed in the churn-body, and the driving-shaft is then rapidly 80 rotated in one direction. As the shaft is rotated its crank-arms, moving through the slots of the levers, will impart an oscillatory motion to the said levers, and this motion will be communicated to the dasher-rod 85 through the belt, so as to vibrate the dasher-rod and the dasher-blades carried thereby. By this means the cream in the churn will be alternately thrown in opposite directions, so that it will be violently agitated and the butter 90 quickly formed. When the butter has been formed, the belt V is unfastened, so that the lid of the churn-body and the dasher can be removed to allow access to be had to the butter.

95 It will be seen that I have provided a very efficient churn in which the parts are compactly arranged and are strong and durable. The driving-shaft can be easily rotated, and, through the oscillating levers and the belt, 100 will vibrate the dasher very rapidly. The churn-body is secured to the base, so that it

will be immovably supported thereon, and cannot shift about as the machine is operated. Having thus described my invention, what I claim, and desire to secure by Letters Patent, 5 is—

As an improvement in churns, the combination of the dasher-shaft, the standards D D, the oscillating levers P, pivoted at their lower ends between the standards D D, and provided 10 near their upper ends with the longitudinal slots Q, the belt V, having its central portion wrapped around the dasher-shaft and its ends secured to the upper ends of the levers

P, and the shaft journaled on the standards D D, and having its crank-arms engaging the 15 slots Q of the levers, the lateral portions of the crank-arms being flattened and engaging the sides of the levers, substantially as specified.

In testimony that I claim the foregoing as 20 my own I have hereto affixed my signature in presence of two witnesses.

DAVID STEPHENS.
